COMBINATION HOSIERY RIDER AND HANGER

Donald J. Silver, High Point, N.C., assignor to Silver Knit Hosiery Mills, Inc., High Point, N.C., a corporation of North Carolina

Filed May 1, 1961, Ser. No. 64,989

Term of patent 3½ years

(Cl. D80—8)

FIG. 1 is a front elevational view of a combination hosiery rider and hanger showing my new design, the socks shown in broken lines being for illustrative purpose only;

FIG. 2 is a front perspective view thereof;

FIG. 3 is a rear elevational view thereof; and

FIG. 4 is a left side elevational view thereof.

What I claim is:

The ornamental design for a combination hosiery rider and hanger, as shown.
